SOUND INDICATING APPARATUS

Willard P. Place, Penn Township, Allegheny County, and Frederick C. Smith, Wilkinsburg, Pa.

Application November 5, 1936, Serial No. 109,392

5 Claims. (Cl. 181—0.5)

Our invention relates to sound indicating apparatus, and particularly to such apparatus which is selectively responsive to the vibrational frequency of sound.

5 One feature of our invention is the provision of means for visually indicating to a musician the accuracy with which any given note is being played or sung, or for indicating sound for any other purpose according to its vibrational frequency.

10 We will describe one form of apparatus embodying our invention, and will then point out the novel features thereof in claims.

In the accompanying drawing, Fig. 1 is a diagrammatic view showing one arrangement of electrical circuits and associated devices for use in apparatus embodying our invention. Fig. 2 is a view, in side elevation, showing an arrangement of gears and shafts through which a vertical disc D is rotated by a motor M, in apparatus embodying our invention. Fig. 3 is an enlarged view, in front elevation, of a portion of disc D shown in Fig. 2. Fig. 4 is a view, also in front elevation, of a control and indication panel A for apparatus embodying our invention.

25 Similar reference characters refer to similar parts in each of the views.

Referring first to Fig. 1, the devices here shown are a microphone P; a transformer T1 having a primary winding 1 and a secondary winding 2; a transformer T2 having a primary winding 3 and secondary windings 4—5, 6, 7 and 8; an amplifier tube 27, of the indirect heater type, having a grid 9, cathode 10, filament 11, and a plate 12; a grid glow tube GG having a grid 13, filament 14, and a plate 15 (some other suitable source of light may be used instead of grid glow tube GG); an inductor L; a rectifier tube 80; a synchronous motor M; a circuit closer S, which may be of the snap switch type, for connecting motor M and primary winding 3 of transformer T2 with a source of alternating current which may be of 60 cycle frequency, the terminals of which are designated x and o; condensers designated by the reference character C with distinguishing numerals; resistors designated by the reference character R with distinguishing numerals; a switch N for connecting to various parts of resistor R9 for varying the grid bias of tube 27; and ground connections designated by the reference character n with distinguishing numerals.

In Fig. 2, a gear EM is shown mounted on the shaft of motor M for driving shaft H1 through gear EH. Shaft H1 is supported on bearings

B1. A hollow shaft H2 is arranged to slide along shaft H1, and may be rotated with shaft H1 by splines 17 set in shaft H1. Shaft H2 carries a plurality of gears, three of which, E1, E2 and E3, are shown here. For use of musicians, shaft H2 may have a gear E for each octave of the musical scale. A gear shift lever F is provided for setting shaft H2 in various given positions along shaft H1. A shaft H3, supported on bearings B2, carries a plurality of gears corresponding in number to the gears carried by shaft H2. In one position of shaft H2, gear E1 will mesh with gear E4 of shaft H3, as shown in the drawing; in a second position of shaft H2, gear E2 will mesh with gear E5; and in a third position of shaft H2, gear E3 will mesh with gear E6 of shaft H3. On the left-hand end of shaft H3, as shown in the drawing, a circular disc D is mounted.

Passing through disc D, are holes arranged in circles concentrically about the axis of disc D a portion of which is shown in an enlarged view in Fig. 3. As here shown, there are twelve such circles, corresponding to the seven tones and five semi-tones beginning with C and ending with B in any given octave of the major musical scale. Grid glow tube GG is mounted back of the upper portion of disc D, and a control and indication panel A is mounted in front of disc D, as shown in Fig. 2.

As shown in Fig. 4, a screen or sheet U of translucent material, such for example as Celluloid, covers a rectangular opening through panel A. Particularly for the use of musicians, seven lines are ruled across translucent sheet U, and the letters c, d, e, f, g, a and b, are placed adjacent the ends of these lines, as shown in the drawing, to designate the corresponding tones of a musical octave. Switch S, previously referred to in connection with Fig. 1, is mounted on the lower left-hand portion of panel A. A lever or knob K is mounted on the lower right-hand portion of panel A, for operating the gear shift lever F, shown in Fig. 2, through suitable linkage represented by the dash line 16. Switch N, shown also in Fig. 1, is mounted on panel A between switch S and lever K.

In order to obtain an indication of a sound or musical note, a musician or other operator will manipulate switch S on panel A to the closed position; will set switch N according to the loudness of the sound; and will set lever K according to the octave in which the sound is located. The closing of switch S will start operation of motor M, and will energize primary winding 3 of trans-

former T2. Rectifier tube 80 is then energized by transformer T2, and supplies high voltage current through a filter J made up of inductor L and condensers C6 and C7. Microphone P is energized by current from filter J passing through resistor R1.

Microphone P, in response to a given sound or musical note, produces variations in its energizing current corresponding to the vibrational frequency of such given sound or musical note.

10 The current thus varied by microphone P energizes primary winding 1 of transformer T1 and secondary winding 2 of this transformer then applies a voltage correspondingly varied to grid 15 9 of amplifier tube 27. Grid bias is applied to grid 9, through switch N, by a voltage divider resistor R9. Plate voltage is applied to tube 27 from filter J through resistors R6 and R2 arranged in a voltage divider circuit.

20 Amplified higher voltage, varied according to the variations of the microphone current, is applied to grid 13 of grid glow tube GG through the resistance coupling means comprising resistor R1, condenser C4 and resistor R3. The input circuit 25 for tube GG includes ground n3, resistors R2 and R1, condenser C4, resistor R4, grid 13, filament 14, secondary winding 7 of transformer T2, and ground n1. Grid bias is applied to grid 13 by voltage divider R8. Plate voltage is supplied to 30 plate 15 of grid glow tube GG through resistor R5.

Each time the voltage which is applied to grid 13 increases in accordance with a change in the microphone current, tube GG "triggers off" or breaks down in its plate circuit which includes 35 ground n6, resistors R8 and R9 in multiple, secondary winding 4-5 of transformer T2, rectifier tube 80, filter J, resistor R5, plate 15 and filament 14 of tube GG, secondary winding 7 of transformer T2, and ground n7. During the intervals 40 between the times at which tube GG breaks down, condenser C5 is being charged up, by a circuit which is the same as the plate circuit traced for tube GG from ground n6 as far as resistor R5, and then including condenser C5 and 45 ground n4 and when tube GG breaks down, condenser C5 discharges abruptly through tube GG, causing tube GG to emit a brilliant flash of light. In this way, tube GG gives one flash of light for each cycle of the variations in the microphone 50 current. Since the variations in the microphone current are at the vibrational frequency of the sound or note by which they are produced, the flashes of light emitted by tube GG are also at the vibrational frequency of the sound or note to which microphone P responds.

The flashes of light from tube GG shine through the upper portion of the circles of holes in disc D and onto screen U of panel A. When the flashes of light are at the same frequency 60 as the holes in one of the circles pass in front of tube GG, there will be a stationary spot of light on screen U at a point corresponding to the note which is being played or sung.

If, for example, the apparatus were so designed 65 that, for the middle octave of the major musical scale, disc D were rotated at a speed of 60 revolutions per minute, the circle on disc D corresponding to note A would contain 440 holes, since the vibrational frequency of note A is 440 cycles per 70 second. The circles for other notes would have numbers of holes corresponding to the vibrational frequencies of these notes. If, now, note A were sounded accurately, a stationary spot of light would appear on the line marked a on screen U. Streaks of light would at the same

time appear on the lines corresponding to the other six notes, and between some of these lines corresponding to the five semi-tones.

If, on the other hand, note A were inaccurately sounded, so that there were 441 instead of 440 flashes of light per second, the flashes of light would get farther and farther ahead of the holes in the circle for note A, and hence, if the disc were turning in the clockwise direction, the spot of light, and other similar spots in succession, would move to the left. If the flashes of light were slightly less than 440 per second, the spots of light would move to the right.

It follows that when there is a stationary spot of light for any given note, the musician will 15 known that the note is being accurately sounded, and if the spot moves to either the left or the right, the proper correction can be made in rendition to cause the note to be correct, as will be indicated by the spot becoming stationary. If 20 the note is inaccurately sounded, the rapidity with which the spots of light corresponding to this note move either to the left or to the right indicates to the musician how badly the note is 25 out of tune.

Although we have herein shown and described only one form of sound indicating apparatus embodying our invention, it is understood that various changes and modifications may be made therein within the scope of the appended claims 30 without departing from the spirit and scope of our invention.

Having thus described our invention, what we claim is:

1. In combination, apparatus responsive to sound for translating sound vibrations into electric current variations having corresponding frequencies, a grid glow tube, means connected to said sound responsive apparatus and to said grid glow tube and responsive to said electric current variations for applying amplified higher voltage correspondingly varied at these frequencies to the grid of said grid glow tube, a plate circuit including a source of current and the plate of said grid glow tube in which said grid glow tube 45 "triggers off" or breaks down each time the voltage which is applied to said grid increases in accordance with said electric current variations, and a condenser connected with said plate circuit and becoming charged during the intervals between the times at which said grid glow tube breaks down and becoming discharged abruptly through said grid glow tube each time said grid glow tube breaks down and thereby causing said grid glow tube to emit brilliant flashes of light. 55

2. In combination, apparatus responsive to sound for translating sound vibrations into electric current variations having corresponding frequencies, a gaseous discharge tube having a plate and a grid, means connected to said sound responsive apparatus and to said gaseous discharge tube and responsive to said electric current variations for applying amplified higher voltage correspondingly varied at these frequencies to the grid of said gaseous discharge tube, a plate circuit including a source of current and the plate of said gaseous discharge tube in which said gaseous discharge tube "triggers off" or breaks down each time the voltage which is applied to said grid increases in accordance with said electric current variations, and auxiliary apparatus controlled by and connected with said plate circuit for applying an additional pulse of current to said gaseous discharge tube each time said gaseous discharge tube breaks down and thereby causing said 70

gaseous discharge tube to emit sharp flashes of light.

3. In combination, sound responsive means for translating sound vibrations into electric current variations having corresponding frequencies, a gaseous discharge tube having a plate and a grid, means connected to said sound responsive means and to said gaseous discharge tube and controlled by said electric current variations for applying 10 amplified higher voltage correspondingly varied at the same frequencies to the grid of said gaseous discharge tube, means connected to said gaseous discharge tube for applying grid bias to the grid of said gaseous discharge tube, a plate circuit including a source of current and the plate of said 15 gaseous discharge tube in which said gaseous discharge tube "triggers off" or breaks down each time the voltage which is applied to said grid increases in accordance with said electric current variations, and a condenser connected with said 20 plate circuit and becoming charged during the intervals between the times at which said gaseous discharge tube breaks down and becoming discharged abruptly through said gaseous discharge tube each time said gaseous discharge tube breaks 25 down and thereby causing said gaseous discharge tube to emit sharp flashes of light.

4. In combination, apparatus responsive to given musical tones for translating a series of vibrations of each of said musical tones into cycles of electric current variations having frequencies corresponding to the frequencies of the vibrations 30

of said musical tones, a device capable of emitting light, means connected to said tone responsive apparatus and to said device and responsive to said electric current variations for applying correspondingly varying current to said device, and 5 auxiliary apparatus connected to said device and controlled by said electric current variations for applying an additional pulse of current to said device for each of said cycles of electric current variations for controlling said device to emit a 10 sharp flash of light for each of said pulses of current.

5. In combination, apparatus responsive to given musical tones for translating a series of vibrations of each of said musical tones into cycles 15 of electric current variations having frequencies corresponding to the frequencies of the vibrations of said musical tones, a device capable of emitting light, means connected to said tone responsive apparatus and to said device and responsive to 20 said electric current variations for applying correspondingly varying current to said device, and means connected to said device and controlled by said electric current variations for applying additional current to said device during a portion of 25 each of said cycles of electric current variations for controlling said device to emit a flash of light during such portion of each of said cycles of electric current variations.
